ATTORNEY.

UNITED STATES PATENT OFFICE

2,321,619

START-STOP REPEATER APPARATUS

Louis M. Potts, Evanston, Ill., assignor to Teletype Corporation, Chicago, Ill., a corporation of Delaware

Original application November 30, 1934, Serial No. 755,253, now Patent No. 2,262,856, dated November 18, 1941. Divided and this application March 3, 1941, Serial No. 381,461

10 Claims. (Cl. 178—72)

The present invention relates to printing telegraph systems and particularly to signal repeating equipment therefor.

This application is a division of copending application Serial No. 755,253 filed November 30, 1934, now Patent No. 2,262,856, granted Nov. 18, 1941.

In telegraph signaling systems where relatively high speed start-stop permutation code signals are employed in the transmission of messages over comparatively long circuits, regenerative repeating apparatus is employed for renewing and reproducing code signals in accordance with the original transmitted signals whereby signal distortions or variations are eliminated and whereby the precise characteristics of each signal, impulses or impulse are reproduced under the control of the code combination signals received over the circuit. Where two remote stations are in communication each with the other, as through the medium of an interconnecting or central office station, there may be employed an intermediate repeating device capable of operating at high speeds for reproducing in original strength and wave shape each signal generated by either of said stations. Under such conditions of communication between two outlying stations, special apparatus has been provided to be used with a repeater unit associated with each station responsive to the establishment of communication by the other of said stations whereby signals transmitted to such station will not cause the repeating apparatus for the receiving station to be released for signal reproducing purposes. In this manner there is prevented the transmission back or reflection over the transmitting leg of the circuit, signals directed to a receiving station.

Accordingly, the principal object of the present invention is to provide repeating apparatus capable of operating at high speeds to transmit signals over a communication line equivalent in strength and wave shape to the originally transmitted signals and without effecting the transmission back of reflected signals to the transmitting station.

The foregoing and other objects of the present invention are attained by the provision of motor driven mechanically operated but signal controlled repeating apparatus for reproducing all signals including start and stop impulses from one communication line section to another, with elements mechanically controlled for preventing the reflex transmission of signals effective at the beginning of each code combination of impulses

and continuing so until the end of such code combination of impulses.

In its preferred embodiment, the present invention utilizes two regenerative devices or units each of which includes a cam operated contact set in which the contacts of the device are positioned in accordance with the character of incoming signal impulses and the setting timed by means of a motor driven series of cam projections. In addition, latching means are provided to prevent an inactive one of a pair of repeater devices from operating during the period of transmission by the active one of said devices of a complete series of signals or signal impulses constituting a character of a start-stop permutation code. By this arrangement there is prevented the release of an inactive repeater unit as a response to the line signals generated by an active one of a pair of units.

For a more comprehensive understanding of the present invention, reference is had to the accompanying drawing and to the following detailed specification, wherein like reference characters designate corresponding parts throughout and wherein

Fig. 1 is a diagrammatic circuit illustration of two line sections and a mechanical system of interlocking members connecting together two regenerative repeater mechanisms in a single telegraph transmission line; and

Fig. 2 shows a motor control system wherein either of two connected regenerative repeater devices may control a common motor which drives both of said devices.

Referring now more particularly to the illustration in Fig. 1, the reference characters 167 and 168 illustrate two regenerative repeater units serving two sections of a single telegraph line and having a mechanical system of interlocking members which will now be described. In this figure is illustrated only the repeating equipment, but it is to be understood that the distant end of each line section 216 and 218, respectively, may be provided with the conventional printing telegraph transmitting and receiving devices.

Each repeater comprises identically the same parts bearing the same reference numerals, except that in the case of the repeater for line section 216 the reference numerals are distinguished from those applied to the parts of the repeater for line section 218 by the provision of a prime mark. The signal pattern determining cams of each repeater unit 167 and 168 are driven upon a shaft 234 and are carried upon a frictionally driven start-stop cam sleeve 171 which carries

four cam or latching discs indicated 172, 173, 174, and 175.

The start disc designated 172 is held by a latch 181, see also Fig. 2, which in turn is pivoted at 182 and which is provided with a holding tooth that restrains disc 172 by fitting into a notch or recess in the periphery thereof. A start latch 183 also pivoted at 182 is restrained by its engagement with armature 184 while the armature is in its attracted or marking position during the energization of magnet 185. Start latch 183 has a sidewardly extending projection 186 which may engage and correspondingly depress the stop latch 181 to cause the latter to become disengaged from and accordingly release disc 172. Start latch 183 also has a cam follower projection 187 which rides the periphery of restoring cam 173 which reconditions said latch 183 after each release by its armature 184.

Coincident with the start impulse intervals of each code combination signal, magnet 185 is de-energized, releasing its armature 184 to the influence of return spring 191, whereupon said armature 184 is permitted to assume its so-called spacing position. At this particular instant in the cycle of rotation of cam sleeve 171 the depression in the periphery of cam 173 is disposed opposite projection 187 of lever 183, thereby permitting said lever 183 to rotate counterclockwise under the influence of its spring 192 when, as just described, armature 184 is withdrawn from beneath its left extremity as may be seen in Fig. 1. Spring 192 being of superior force to spring 193 of latch lever 181, the rotation in a counterclockwise direction on the part of lever 183 about its pivot 182 acts through sidewardly extending projection 186 to carry with it latch 181, thereby lifting the latter's holding tooth out of engagement with the shoulder on the periphery of disc 172.

As a consequence of the withdrawal of latch 181 from disc 172, cam sleeve 171 is permitted to enter upon one cycle of rotation, carrying with it cam disc 172 and cams 173, 174, and 175. Immediately that the depression in cam 173 passes over the location of projection 187, its continuous apex surface causes lever 183 to be cammed in a clockwise direction to resume its original position, as indicated in Fig. 1. As a consequence of the rotation of cam 175, its several apices 177 successively engage the follower projection 213 of a floating contact controlling member 201.

Of principal importance in connection with the present invention, however, is the effect of cam disc 174 during the aforescribed cycle of rotation, in which the sole depression in its periphery is moved past the location of the follower projection 195 of a lever 196 pivoted at 197 presenting during the remaining portion of the rotary cycle to said projection 195 the continuous peripheral apex of said cam disc 174 and holding said lever 196 in an extreme clockwise position against the tendency of the mutual spring 199, which connects said lever 196 with a companion lever 196' relating to the auxiliary repeater apparatus 168 associated with the principal apparatus 167 now being described.

The opposite end of lever 196 terminates with a latching projection 198 which extends within a slot formed in an armature 184'. When the follower projection 195 of lever 196 is aligned with the recess in cam 174, lever 196 is permitted to rotate counterclockwise about its pivot 197, 75

withdrawing the latching projection 198 from engagement with a cooperating shoulder in the slot or notch of armature 184', but when said follower projection 195 is cammed outwardly as 5 by the continuous apex of cam 174, then lever 196 is rocked clockwise about pivot 197, causing the latching projection 198 to engage firmly against the inside slot surface of said armature 184', holding said armature in its marking position notwithstanding the fact that its controlling magnet 185' may subsequently become deenergized.

As a result of the rotation of cam disc 175 having the plurality of cam projections 177 which engage the follower projection 213 of floating member 201, there will be communicated to said member 201 a number of movement impulses corresponding to the number of cam projections 177. Member 201 is principally 15 supported upon a shaft 202 which fits into an open slot at one end thereof and within which it is mildly urged by a seating spring 203. At its opposite end member 201 is formed with an armature engaging fulcrum projection 214. Accordingly, when armature 184 is energized by magnet 185 and held in the left position as 20 viewed in Fig. 1, fulcrum 214 is clear of the armature extremity, so that when a cam projection 177 engages follower projection 213, 25 member 201 will be permitted to pivot about shaft 202, fulcrum 214 rising upwardly together with contact lever operating projection 212. However, when said armature 184 is released as 30 by the deenergization of its magnet 185, then an innermost surface thereof is placed over said fulcrum projection 214 so that thereafter when one of the cam projections 177 engages follower projection 213, the movement upward on the part of member 201 is resisted because of the 35 abutment between fulcrum projection 214 and the inner surface of said armature lever 184, causing instead the right extremity of said member 201 to become unseated from shaft 202 against the influence of spring 203, whereupon 40 the contact lever operating projection 211 will rise to engage the mutual operating lever 204.

Depending upon whether projection 211 or projection 212 engages said lever 204, the latter will 45 accordingly be disposed about its pivot screw 205 in the position as indicated in Fig. 1, or in its alternative position whereat its extremity is withdrawn from closing contact pair 206, both 50 positions being maintained by a detent jockey 207 under the influence of a spring tensioned bell crank. Since armature 184 will be positioned to the left or to the right, depending upon whether a code combination signal is comprised accordingly of marking or spacing impulses, the effect 55 of each cam lobe or apex 177 upon the contact operating member 201 will accordingly be to close or open the contact pair 206 and to correspondingly reproduce a signal upon line 218, the permutational character of which will be controlled by the line impulses impressed upon magnet 185, 60 but the precise wave shape of which will be controlled invariably by the disposition of the cam apices 177.

As a result, the reproduced signals on line 218 will partake of a wave shape corresponding to the original signals or, more accurately, to the shape of theoretically perfect signals, cam 175 being especially designed to obtain this result, 65 though said signals impressed upon line 218—219 will have no effect upon the auxiliary repeating device since its armature 184' will be held sta-

tionary during the entire cycle of each signal on account of the shape of cam disc 174 acting upon lever 196 and armature 184'. For a better understanding of the details of construction of repeating apparatus such as that diagrammatically illustrated in Fig. 1, reference may be had to U. S. Patent No. 2,104,273 to L. M. Potts granted January 4, 1938.

During communication in the opposite direction, that is, from line 218 with the repeater unit 168 having the prime reference markings as the principal or effective machine, the result will be just reversed to the aforescribed manner of operation, with shaft 234' and its repeating unit including sleeve 171' rotating cyclically under the control of signals impressed upon lines 218-219 and effective to accordingly energize and deenergize the winding of magnet 185'. Some difference may be noted in the shape of lever 196' as compared with that of the first described intercontrol lever 196. This difference is of a casual significance, however, since as may be noted the effective intercontrol between the two repeating units is identical. When cam disc 174' rocks lever 196' in a counterclockwise direction through engagement with its follower projection 195', the remotely situated armature blocking projection 195' acting upon armature 184 will effectively hold in abeyance the unit 167, just as in the aforescribed manner of operation unit 168 was held in abeyance by the effective operation of unit 167.

It is to be noted that contact controlling lever 204 whose extremity forces into engagement with each other the contact points 206 when said lever 204 is in clockwise position or permits the latter members to come ajar when said contact lever 204 is in counterclockwise position, partakes of the nature of a controlling element which is effectively moved from marking to spacing and vice versa only where a succeeding line impulse differs from a preceding one in essential signalling characteristics. That is, where consecutive impulses are of the same essential signalling characteristic, member 204 under such conditions operating in a similar manner finds said lever 204 repeatedly in the same position held by detent jockey 207 and since no change is produced upon said lever 204, none will be had upon the contact pair 206.

Interruption in the transmission is effected by opening the receiving line section for a sufficient period or interval whereupon during the stop signal condition of the transmitting line section the open circuit condition of the receiving line section will operate to seize the alternative repeating mechanism and to render the home recorder of the particular transmitting station unresponsive to the operating transmitter. In this way the transmitting operator is notified at his station that the receiving station is desirous of transmitting a message.

In Fig. 2 there is shown additionally to the disclosure of Fig. 1 a motor control mechanism for the apparatus wherein a single motor drive system imparting rotation to both repeater units 167 and 168 is controlled to start by a signal in either of the two associated line sections.

Upon a supporting panel 231 there are mounted two fixed supporting brackets indicated 232 and 232', each of which affords journal bearings, respectively, for its associated one of the two shafts 234 and 234'. As has been said, a cam sleeve 171 is carried upon each one of said shafts and each is driven through a friction clutch 236.

Also fixed upon the pivot rods 182, described above, are cam followers 238 and 238', the extremities of which follow in the thread of cam screws 240 and 240'. The cam screws are slideable upon their respective shafts 234 and 234' and are at all times under the tension of associated springs 242 and 242' being rotatable with their respective shafts through a longitudinally shiftable spline connection 241'. In close proximity to the screw cams 240 and 240' are an associated pair of snap switches generally indicated 244 and 244' each with an operating arm 246 engageable by the extremity flanges of its associated screw cams designated 248 and 250.

10 In operation, cam follower 238 of each unit is stationary, longitudinally, but through its engagement with the threads of its associated worm the latter member including its extremity flanges 248 and 250 is moved as a unit by reason of rotation of the shaft 234 when the follower 238 engages the threads of its screw. When the assembly 248-250 moves toward the mounting panel 231, flange 248 will engage switch arm 246 and move the latter so as to permit the opening of its associated contact pair 252.

15

The rotary driving motor 254 driven from a source of power 255 when either of the contact pairs 252 or 252' is closed, operates through gear train 256 to drive a distributor shaft 257 which carries a tributary driving worm for driving each one of the repeater drive wheels 258 and 258'. The effect of control switches 244 and 244' upon the motor operating circuit is as follows: Receipt of a starting signal of spacing characteristic by line magnet 185, for example, deenergizes the latter element and releases its armature 184, which by spring 191 is drawn from beneath its associated latch 183 permitting the latter to rotate freely upon its supporting shaft 182. In so doing, projection 186 of lever 183 causes to be similarly rotated the latch lever 181 which normally holds against rotation the cam assembly 171, releasing the latter to clockwise rotation as viewed in Fig. 1. Since each of the latch levers 181 is keyed to its associated shaft 182, the counterclockwise rotation of said latch lever 181 will accordingly withdraw the cam follower 238 from the thread of its associated worm 240. As a result, worm 240 will thereby be free to respond 20 to the urge of its spring 242 and be thrust upwardly, as viewed in Fig. 2, until its flange 250 engages the extremity of switch arm 246, causing the latter to be snapped to its contact closing position.

25 In consequence, contact pair 252 will become closed completing the circuit to motor 254 which will begin rotation and accordingly will impart rotation to shafts 234 and 234'. Thereafter, during the conclusion of each cycle of rotation when latch lever 181 is permitted to resume its latched position as indicated in Fig. 1, cam follower 238 will be permitted to reengage the threads of its associated worm 240 and cam assembly including the worm 240 and the discs 248 and 250 will again approach the panel 231 until a subsequent start signal repeating the aforescribed release operation to armature 184, lever 183, and latch 181, again withdraws cam follower 238, in consequence of which cam assembly 240 and discs 248 and 250 will again be restored to the position for effecting contact closure.

30 However, since contact arm 246 remains in contact closing position until such a time that worm follower 238 has remained within the threads of its worm 240 long enough to feed disc 248 down-

wardly to engage switch arm 246, the repeated release operations of worm 240 will be of such short duration as to have no effect upon the associated switch mechanism 244.

After the cessation of signalling, the absence of start signals will permit cam follower 238 to remain continuously in engagement with its associated cam worm 240 for an interval of time sufficient for cam 240 to move toward panel 231 until its flange 248 engages arm 246 to reverse the mechanical condition of snap switch 244, thereby opening its associated contact 252 to interrupt the circuit and accordingly to arrest the further rotation of motor 254.

When breaking the transmission line, as described in connection with Fig. 1 above, the original transmission over controlling line section 216 will operate motor 254 by control of the contacts 252 and the line break under the control of line section 218 will operate latch 181' and cam follower 238' to reverse the mechanical condition of snap switch 244' to close its contact points 252' so that for a brief interval motor 254 will have its power circuit closed by contacts 252 and 252' in parallel. Accordingly, each of the snap switches 244 and 244' will be reversed to open its contacts under the control of its associated cam 240 or 240' by control of its own line section 216 or 218, and independently of the continuation or cessation of transmission under the control of the associated one of said pair of line sections. For this reason motor 254 may stop only when transmission has ceased upon both line sections for the duration of a suitable period of time.

While the present invention has been explained and described with reference to a particular embodiment thereof, it will be understood that certain changes and modifications may be adapted without departing from the spirit or scope thereof. Accordingly, it is not intended to be limited by the details of the accompanying drawing nor by the specific language in the foregoing description except as indicated in the hereunto appended claim.

What is claimed is:

1. In a telegraph repeating system, two line sections, two regenerative repeaters each comprising a cyclically rotatable signal pattern outlining member, one of said repeaters associated with each of said line sections to repeat impulses into the other of said line sections, and mechanical interlocking means interengaging said two members to prevent concurrent operation of said two members.

2. In a telegraph repeating system, two line sections, two regenerative repeater mechanisms each for repeating impulses from one of said line sections into the other of said line sections, a motor to drive said repeating mechanisms, a power supply circuit for said motor, a first contact pair operable in response to an initial signal in one of said two line sections, and a second contact pair operable in response to an initial signal in the other of said two line sections, said first and second contact pairs connected in parallel in said power supply circuit to control said circuit alternatively and jointly.

3. In a telegraph repeating system, two line sections, two regenerative repeaters comprising cyclically rotatable members, one of said repeaters associated with each of said line sections and each having an armature responsive to signals in its line section to release for rotation its associated member to repeat impulses into the other line section, and means moved by one of

said members into position to obstruct the armature of the other of said members.

4. In a telegraph repeating system, two line sections, two regenerative repeaters one associated with each of said line sections, movable parts in each of said repeaters released for cyclic operation by signals in its line section to repeat impulses into the other of said line sections, and mechanical means extending between said two repeaters operable by a movable part of one of said repeaters and placeable into the path of the movable part of the other of said repeaters for obstructing said other of said two repeaters during the cyclic operation of said one of said 15 movable parts.

5. In a telegraph repeating system, two line sections, two regenerative repeaters including cyclically operative mechanisms, one repeater associated with each of said line sections to repeat 20 impulses in one direction only into the other of said line sections, and means movable by the mechanism of one of said repeaters and interposed to prevent concurrent operation of the other of said mechanisms.

6. In a telegraph communication line, two regenerative repeaters each associated invariably with signal communication signals in one direction over said line and each having an armature to repeat impulses over said line and a rotatable member for determining the impulse periods of each signal, and means mechanically operated by one of said repeaters to obstruct the operation of the other of said repeaters to prevent the movement of the rotatable member of 30 the other repeater during the transmission of communication signals in the direction associated with said one of said repeaters.

7. In a telegraph repeating system, a line of communication comprising a plurality of consecutive line sections, a regenerative repeater mechanism associated with each of said line sections, a movable part associated with each of said repeater mechanisms for demarking duplicate signals corresponding to signals incoming upon its 45 line section, electromagnetic means responsive to initial impulses of said incoming signals for releasing to cyclic operation its associated one of said movable parts, and mechanical means extending between one of said regenerative repeaters to another operable by said movable part of one of said repeaters to obstruct the manner of action of said other of said repeaters.

8. In an intercommunication telegraph system, two line sections, regenerative repeater 55 mechanisms to repeat impulses into either of said line sections, a normally nonoperating motor rotatable to drive said repeating mechanisms, a power supply circuit for said motor, a contact operable in response to an initial signal in one 60 of said two line sections, and a further contact operable in response to an initial signal in the other of said two line sections, said contacts and said further contacts connected in parallel in said power supply circuit to control said circuit by either contact.

9. In a communication line for permutation code telegraph signals, a pair of line sections, a rotatable signal reshaping apparatus associated with each of said line sections, a common power source for said apparatuses, a magnet in each line section for controlling the application of power from said source to the apparatus for reshaping of signals for the other of said pair of line sections, and a control circuit including 75 parallel control switches associated with each of

said apparatuses for supplying current to said source during the continued operation of either of said apparatuses.

10. In a repeating system, two line sections, a start-stop regenerative repeater associated with each of said sections for reproducing multiple-impulse signals, a cyclic motion element associated with each one of said repeaters, a control member with each of said repeaters re-

sponsive to the initial impulse of said multiple impulse signals to release its repeater for rotation, a member extending from each one of said elements to the other one of said elements so as to prevent the release of said other of said repeater elements during the cyclic motion of its said element.

LOUIS M. POTTS.
